UNITED STATES PATENT OFFICE.

DAVID UMANOFF, OF NEW YORK, N. Y.

TEMPORARY BINDER.

1,159,135.

Specification of Letters Patent. Patented Nov. 2, 1915.

Application filed September 25, 1914. Serial No. 863,429.

To all whom it may concern:

Be it known that I, DAVID UMANOFF, a citizen of the United States, a resident of the borough of Brooklyn, county of Kings, city and State of New York, have invented certain new and useful Improvements in Temporary Binders, of which the following is a specification.

This invention relates to a paper clip or clamp, adapted for use as a temporary binder. These devices are mainly used for temporarily holding a number of sheets of paper, letters or the like, and usually comprise a clamp mounted within a foldable cover.

The invention consists primarily in the peculiar construction of the clip, whereby the parts thereof may be assembled and secured in their operative position within the minimum of labor, and wherein only one of the parts of the device is permanently secured in position, this one part serving to hold all of the other parts of the device in their proper places.

The invention further consists in the novel construction and arrangement of the parts, all of which will be fully hereinafter described.

In the drawing Figure 1 is a perspective view showing the clamp or paper-holding clip in position within a foldable cover; Fig. 2 a plan view of the clamp; Fig. 3 a transverse sectional view showing the clamp closed; and Fig. 4 a similar view showing the clamp open.

Referring to the various parts by reference characters, A designates the book cover within which the clamp is secured; and B the papers held by the clamp.

The paper-holding clip consists of three main or principal parts or elements, the base plate 1; the clamping-jaw 2, and the opening cam 3. The base 1 consists of the bottom plate 4, which is turned up slightly at its forward edge to form a clamping edge 5. The ends of this base plate are turned upwardly to form the lugs 6. Between these lugs, and near their forward edges, is pivotally mounted the opening cam 3, said cam being provided at its ends with bearings or pivots 7, which fit loosely in apertures in the upstanding lugs 6. The cam 3 is formed near its ends with the slightly curved cam-fingers 8, the convex side of said fingers being uppermost and adapted to engage on the

under side to clamp jaw 2, all of which will be more fully hereinafter described. The jaw-opening cam 3 is provided near its center with an integral forwardly extending lever or finger-piece, 9, which projects 60 through an aperture in the clamping-jaw and in its normal position extends forwardly over said jaw as shown in the drawings.

The clamping jaw in its normal clamping position extends from the forward edge 5 of base 1 upwardly and rearwardly to a point directly over and close to cam 3. From this point said jaw curves downwardly and then upwardly forming the concave or substantially semi-circular channel 10, the under side 70 of said channel bearing on the base plate 1. In this channel is arranged a coil spring 11, one end 12 of said spring bearing on the upper side of the clamping-jaw forward of the axial line of the cam 3. The other end 75 13 of this spring bears on the base plate at the rear edge thereof, and in the rear of the spring coil 11. The rear edge of the clamping-jaw is notched or cut out as shown at 17 in Figs. 2, 3 and 4, to permit the end 13 of 80 the spring to bear on the bottom plate near its rear edge. The spring is held in its position in the channel 10 by a pin 14, which extends through the spring and whose ends are rigidly secured in the lugs 6. The 85 clamping-jaw is formed with the aperture 15 through which the finger-piece 9 extends.

In the normal or clamping position of the jaw 2 its forward edge will engage the forward edge of the base plate 1, at the clamping edge 5, and the under side of the channel part 10 will bear on the upper surface of the base 1 directly under the spring coil 11, as shown in Fig. 2. By forming the channel part 10 so that it partly encircles the spring 95 11 the said clamping-jaw is held against any backward or forward movement. It is therefore unnecessary to pivot the clamping-jaw in the lugs 6, or to the base plate. The clamping-jaw extends above the cam 3 so 100 that the strain of the spring 11 will not be brought on the cam, except, of course, when the clamping-jaw is opened or raised by means of the cam 3. The pivots of the cam 3 are loosely mounted in the lugs 6, so that in the assembled devices the only parts permanently and rigidly connected together are the pin 14 and the lugs 6 of the base plate. When the clamping-jaw is raised by means 105 of the cam 3, the curved channel part 10 110

moves around the spring 11, as clearly shown in Figs. 3 and 4, thereby rendering it unnecessary to pivotally mount the clamping-jaw in the lugs 6. In order to open the 5 clamping-jaw the finger-piece or lever 9 is forced upwardly and rearwardly. This brings the convex surfaces of the cam fingers 8 against the under side of the clamping-jaw in front of the curved part 16 which 10 over-lies the cam 3. The lever 9 is then forced rearwardly until the ends of the cam fingers 8 are in the rear of a vertical line drawn through the axis of the cam 3. In 15 this position of the cam the operating finger 9 is against the rear edge or wall of the aperture 15, and the cam locks the jaw open and against the tension of the spring 11. When it is desired to close the clamp the lever 9 is moved forwardly, and as soon as the cam 20 fingers 8 pass forwardly beyond the vertical position, the spring will throw the jaw downwardly to its closed position. It will, of course, be understood that the clamp or clip may be used in any position and that 25 the base plate need not necessarily be horizontal. It will also be understood that the position which has been described as vertical, is a line perpendicular to the bottom plate 4 of the base and extending through 30 the axis of the cam 3.

It is to be noted that when the clamping-jaw is in its operating position it extends over and is free of the cam 3. This is an 35 advantage for the reason that the small bearings or pivots 7 of the cam are not subjected to the strain and wear which would be on them if the clamping-jaw engaged the cam in its closed position.

What I claim is:

40 1. A clip for a temporary binder comprising a base plate, a clamping-jaw, an opening cam between the jaw and the base plate, a spring for yieldingly holding the clamping-jaw, the rear end of the jaw extending between the spring and the base plate said spring serving as means for holding the jaw in position on the base plate.

2. A clip for a temporary binder comprising a base plate, a clamping-jaw, an 50 opening cam arranged between the jaw and base plate and adapted to move the jaw away from the base plate, a spring for holding the clamping-jaw, a portion of the clamping-jaw in the rear of the opening cam extending between the spring and the base plate, whereby the spring and the opening cam will serve as means for holding the clamping-jaw in position.

3. A clip for a temporary binder comprising a base plate, a clamping-jaw, an 60 opening cam between the jaw and the base plate, that portion of the jaw in the rear of the cam being formed to provide a transverse semi-cylindrical groove or channel, a 65 coil spring arranged in said groove and en-

gaging the jaw and the base plate, and rigid means for permanently securing the spring in place.

4. A clip for a temporary binder comprising a base plate, a clamping jaw, an 70 opening cam between the jaw and the base plate the said clamping jaw in the rear of the opening cam extending close to the base plate and being formed to provide a groove or channel extending parallel with the 75 clamping edge of the jaw and the under surface of said channel portion being adapted to contact with the base when the jaw is closed, a coil spring located in said channel, one end of said spring bearing on the clamping-jaw and the other end of said spring bearing on the base plate, and means for 80 permanently securing the spring in position.

5. A clip for a temporary binder comprising a base plate, a clamping jaw, an 85 opening cam arranged between the jaw and the base plate, an operating lever formed on the opening cam and projecting forwardly through an aperture in the clamping jaw, a portion of the jaw in the rear of the opening 90 cam extending downwardly to the base and formed to provide a channel extending parallel with the clamping edge of the jaw, a coil spring arranged in said channel and having one end bearing on the clamping jaw 95 forward of the opening cam and the other end bearing on the base plate, a rod extending through said coil spring, and means for permanently and rigidly securing said rod to the base plate, whereby the spring and the 100 cam serve as means for holding the clamping jaw to the base plate.

6. A clip for a temporary binder comprising a base plate, a bodily movable and swinging clamping jaw, an opening cam 105 between the jaw and the base plate, a coil spring extending across the rear end of the clamping jaw and yieldingly holding the said jaw in its closed position and retaining the rear end of the jaw between the spring 110 and the base plate.

7. A clip for a temporary binder comprising a base plate, a bodily movable clamping jaw, an opening cam between the jaw and the base plate, a coil spring extending 115 across the rear end of the jaw and forming a cylindrical bar about which the rear end of the jaw may turn, one end of said spring serving to hold the jaw yieldingly in its closed position.

8. A clip for a temporary binder comprising a base plate, a clamping jaw having its rear end formed into a transversely extending channel, a coil spring extending 125 across the rear end of the clamping jaw and arranged within the said channel and forming a bar about which the rear end of the clamping jaw may move, one end of said spring bearing on the clamping jaw and yieldingly holding it in its closed position.

9. A clip for a temporary binder comprising a base plate formed with two upwardly extending end lugs, an opening cam pivoted in said lugs and formed with an operating lever, a bodily movable clamping jaw loosely fitted between the lugs and extending over the opening cam, the forward edge of said jaw constituting the clamping edge, said jaw in the rear of the opening cam being formed into a transversely extending channel below the pivot of the opening cam, a coil spring extending across the rear end of the clamping jaw and fitting into said channel and serving as a retaining means for the clamping jaw and forming a cylindrical bar about which the rear end of the jaw may move, one end of said spring yieldingly holding the clamping jaw in its closed position and the other end of the spring bearing on the base plate.
10. A clip for a temporary binder comprising a base plate formed with two upwardly extending end lugs, an opening cam pivoted in said lugs and formed with an operating lever, a bodily movable clamping

jaw loosely fitted between the lugs and extending over the opening cam, the forward edge of said jaw constituting the clamping edge, said jaw in the rear of the opening cam being formed into a transversely extending channel below the pivot of the opening cam, 25 a coil spring extending across the rear end of the clamping jaw and fitting into said channel and serving as a retaining means for the clamping jaw and forming a cylindrical bar about which the rear end of the 30 jaw may move, one end of said spring bearing on the upper surface of the jaw forward of the pivot of the opening cam and yieldingly holding the clamping jaw in its closed 35 position, the other end of the spring bearing on the base plate.

In testimony whereof I hereunto affix my signature in the presence of two witnesses.

DAVID UMANOFF.
